UNITED STATES PATENT OFFICE.

JOHN L. GUERRANT, OF SEDALIA, MISSOURI.

FREIGHT-CAR DOOR.

Application filed May 23, 1921. Serial No. 471,888.

To all whom it may concern:

Be it known that I, JOHN L. GUERRANT, a citizen of the United States, residing at Sedalia, in the county of Pettis and State of Missouri, have invented certain new and useful Improvements in Freight-Car Doors, of which the following is a specification, reference being had therein to the accompanying drawing.

10 The present invention relates to freight car doors, and is particularly an improvement over the freight car doors disclosed in my copending application filed Nov. 22, 1920, Serial No. 425,782.

15 It is the object of the invention to provide a freight car door having auxiliary doors to facilitate the filling of the car with grain, sand, or other similar material, and for discharging the material or giving access to the contents behind the car door, so that the car can be emptied conveniently, with novel means for holding the auxiliary and main doors closed under a single seal.

20 Another object is the provision of novel means for mounting the auxiliary doors on the main door, to provide for tight closure and for the convenient opening and closing of said auxiliary doors.

25 A still further object is the provision of novel means for securing and latching the main door to the door frame or car wall, for holding the main door tightly closed, and preventing the escape of grain, sand, or other contents, without the necessity of using an inner grain door as customary, and to also exclude dirt, dust, rain, air and the like, from the car.

30 The invention also has for an object to improve the construction generally and in its details, to enhance the utility and efficiency thereof.

35 With the foregoing and other objects in view, which will be apparent as the description proceeds, the invention resides in the construction and arrangement of parts hereinafter described and claimed, it being understood that changes can be made within the scope of what is claimed without departing from the spirit of the invention.

40 The invention is illustrated in the accompanying drawings, wherein:—

Figure 1 is a face view of the improved door construction.

Figs. 2, 3 and 4 are horizontal sections

taken on the respective section lines 2—2, 55 3—3 and 4—4 of Fig. 1;

Figs. 5, 6, 7 and 8 are vertical sections taken on the respective lines 5—5, 6—6, 7—7 and 8—8 of Fig. 1;

Fig. 9 is an enlarged fragmentary face view of the latch bar and one of the keepers showing the bar in raised position;

Fig. 10 is an edge view of the latch bar and keeper, as seen in Fig. 9;

Fig. 11 is a view similar to Fig. 10 showing the latch bar in lowered position;

Fig. 12 is a view similar to Fig. 7 showing a modification in the upper auxiliary door construction;

Fig. 13 is a face view showing a modified form of locking and sealing device;

Fig. 14 is a face view of a modified form of door construction;

Figs. 15, 16 and 17 are enlarged sectional views taken on the respective section lines 75 15—15, 16—16 and 17—17 of Fig. 14;

Fig. 18 is an enlarged face view of one of the latching and clamping devices of the main door shown in Fig. 14, showing the latch in released position in full lines, and in another position in dotted lines;

Fig. 19 is a vertical section of the latching device, taken on the line 19—19 of Fig. 20 showing the parts in latching position;

Fig. 20 is a section on the line 20—20 of 85 Fig. 19;

Fig. 21 is a section on the line 21—21 of Fig. 18.

The door frame comprises, as usual, the sill 14, and the posts 15 and 16 at the opposite sides of the door opening, and the main car door 17, as shown, is composed of two layers of wood, although it can be of metal, combination wood and metal or other suitable construction. The door is suspended for 95 longitudinal movement along the exterior of the car wall from a suitable track 18' extending over the doorway or opening.

The door 17 and the door frame are provided with means to fit them tightly together for preventing leakage and also excluding the elements from the car. Thus, a metal plate 18 is secured to the outer side of the door 17 along the lower edge or end thereof, and projects downwardly beyond 100 said edge of the door, as seen in Fig. 5. A channel strip 19 has its outer flange overlapping and secured to the lower edge portion 105

of the plate 18, and forms a hook which extends under and behind a depending flange 20 offset outwardly from a rail plate or strip 21 secured to the outer side of the car wall and sill. The offset portion of the strip 21 extends below the door 17, and said door moves over said offset portion, and the hook or channel 19 in engaging under and behind the flange 20 will guide the door 17 and maintain it in position adjacent to the car wall. When the door 17 is in closed position, the lower edge thereof is clamped in place, and for this purpose, outstanding stud bolts 22 are carried by the sill 14, under the rail strip 21, and nuts 23 are threaded on said bolts to bear against the channel or hook 19, when said nuts are screwed inwardly, to thereby press the lower edge portion of the door against the plate or strip 21.

20 A vertical metal strip or plate 24 is secured to the outer side of the door post 16 and has a portion 25 bent outwardly at an angle to form a stop for the door, against which the forward vertical side edge of the door 17 strikes when said door is slid to closed position. The portion 25 has a flange 26 bent at an angle to overlap said portion of the door, and forming a vertical groove or channel into which said portion of the door moves, to hold the door against the post 16 and to prevent leakage.

35 A vertical strip 27 is secured to the forward vertical edge portion of the door 17, to move behind the flange 26 and to abut the stop portion 25, and tongues 28 project from the strip 27 to pass through slots or openings 28' in the portion 25 when the door is closed. Said tongues 28 have the open slots 29 to receive clamping bolts 30 carried by 40 the car wall adjacent to the posts 16, whereby when the door is closed, the tongues 28 thereby move into engagement with the bolts 30, and said bolts can be tightened for clamping the forward edge portion of the door against the plate 24, to prevent leakage.

50 A vertical Z-bar or strip 31 is secured to the opposite or rear vertical edge of the door and outer side thereof, and has a flange 32 extending from said edge of the door adjacent to the inner side of such door. A vertical plate or strip 34 is secured to the post 15 at the outer side thereof, against which the rear edge portion of the door 17 bears when closed, and said plate 34 has tongues or keepers 35 projecting from that edge opposite to the door opening to pass through openings 33 provided in the strip 31, so that when the door is closed, the strip 31 will move over the keepers 35, which project through the openings 33 in front of the flange 32.

55 In order to latch the door 17 in closed position and to clamp the rear edge portion thereof against the plate 34, a vertical latch

bar 36 is slidable longitudinally of itself in guides 37 secured to the front side of the flange 32, and said bar 36 moved behind the keepers 35 when the door 17 is closed. The bar 36 has hooks 38 to move over the keepers 35, and to be moved downwardly into engagement with said keepers, and below the hooks 38 the bar 36 has cams 39 which move behind the keepers when the hooks 38 are moved downwardly into engagement with 70 said keepers. The cams 39 will therefore shift the bar 36 toward the car wall, thereby pushing the flange 32 and rear edge portion of the door toward the car wall and clamping the door 17 against the plate 34 80 on the post 15. When the latch bar is moved downwardly to latching position, the lower end of said bar is secured to the flange 32 by means of a bolt 40, and said flange has a bolt hole 41 higher up, for the reception of the bolt 40 for holding the latch bar in raised or releasing position. The keepers 35 have upstanding lugs 42 to prevent the hooks 38 from sliding off of said keepers, thereby holding the main door 17 in closed 90 position when the latch bar 36 is down.

95 The auxiliary doors 43 and 44 are composed of metal, as shown, and are for the purpose of closing, respectively, an upper filling opening 45 in the door 17, near the upper end or edge of the door, and a lower discharging opening 46 near the lower end or edge of the door 17 with its lower edge preferably flush with the sill 14.

100 In order to mount the relief door 44 across the opening 46, the door 17 is provided along the lower edge of the opening 46 with a groove 47 behind the upper edge of the plate 18, into which groove the lower edge of the door 44 can move downwardly. 105 The door 17 has a groove 48 at the upper edge of the opening 46 behind a channel member 49 secured to the outer side of the door 17 above said opening, for receiving the upper edge of said door 44, and a second channel member 50 is secured to the door 17 above the channel member 49 for purpose of reinforcement. Hinge straps 51 extend downwardly to overlap the door 44, and their upper ends are hinged, as at 52, 110 to the member 49 and are offset, as at 53, whereby said straps can bear flatly against the door 44. Guides 54 are secured to the outer side of the door 44, to receive the straps 51, and to support the door 44 for sliding movement on said straps. Stop screws 55 are removably secured to the lower terminals of the straps to limit the sliding movement of the door 44 on said straps when the door is opened, and when 115 said screws are removed the door can be slid off said straps. An offset lip 56 is secured to the door 44 near the lower edge thereof to overlap the upper edge of the plate 18 opposite to the door 44, said upper edge of 120

the plate 18 being preferably bent outwardly, as at 57.

A metal frame 58 is secured to the door 17 around the filling opening 45, and has an 5 outturned portion 59 at the upper edge of the opening 45 with an upstanding flange 60 forming a hook, and the side portions of the frame 58 have similar hook portions 61. The lower portion of the frame 58 has an 10 outturned portion 62 with an upstanding flange 63 forming a hook or channel similar to the one above. The upper edge portion of the door 43 is bent backwardly and downwardly to form a hook 64 to move downwardly behind the flange 60, and vertical 15 angle bars 65 are secured to the inner side of the door 43 at the vertical edges thereof to move into overlapping relation with the portions 61 at those sides thereof opposite 20 to the opening 45. An offset strip 66 is secured to the door 43 near the lower edge thereof to move downwardly behind the flange 63, with the lower edge portion of said door overlapping said flange on the 25 outer side thereof. Thus, when the door 43 is placed against the frame 58 in a slightly raised position, it can drop downwardly into engagement with said frame, the hook 64 engaging behind the flange 60 30 and the strip 66 moving down behind the flange 63, while the bars 65 overlap the portions 61 to provide a tight fit all around, to prevent leakage.

The door 43 is hingedly suspended similar to the lower door 44. Thus, depending hinge straps 67 overlap the door 43, and their upper ends are hinged, as at 68, to the door 17 above the door 43 and opening 45. Guides 69 are secured to the outer side of 35 the door 43 and are slidable on the straps 67, and removable stop screws 70 are secured to the lower terminals of the straps 67 to limit the sliding movement of the door on said straps. The door 43 can be raised 40 out of engagement from the flanges 60 and 63, to swing open outwardly. The door 43 can also be slid downwardly off of the straps 67 when the screws 70 are removed, when it is desired to allow the door 43 to drop down 45 out of the way, as when it cannot be swung completely open when adjacent to a building or other obstruction. The door 43 can be anchored to the door 17, to prevent loss of the door 43, and, for this purpose, chains or other flexible connections 71 are provided 50 between the lower edge portion of the door 42 and the door 17 below the opening 45.

In order to prevent the doors 43 and 44 from being opened, a pair of vertical bars 60 55 72 and 73 are hingedly mounted to swing against and overlap the right and left hand ends, respectively, of said doors. Said bars 72 and 73 are secured to hinge straps 74, which are hinged as at 75 to the door 17 60 adjacent to the side edges thereof, whereby

said bars are swingable about vertical axes away from and against the auxiliary doors. Stops 76 are secured to the bars 72 and 73 to move over and contact with the upper ends of vertical angle bars or cleats 77 secured to 70 the outer side of the door 44 near the ends thereof, whereby to prevent the door 44 from being raised out of the groove 47, and wooden bars or cleats 78 are secured to the rear side of the bars 72 and 73 to bear 75 against the door 17 between the doors 43 and 44, and prevent said bars 72 and 73 from being bent out of shape should objects strike same between the auxiliary doors. Stops 79 are also secured to the inner sides 80 of the bars 72 and 73 near the upper ends thereof to extend over the upper edge of the upper door 43, when said bars are swung against the auxiliary doors, to prevent the upper door from being raised out of engagement with the frame 58. 85

As a means for holding the bars 72 and 73 in place against the auxiliary doors, straps 80 are secured to the door 17 near the upper edge thereof and have offset portions 81 90 against which the upper ends of the bars 72 and 73 bear when they are swung against the auxiliary door. Latch rings 82 are movably mounted on the offset portions 81 to move downwardly over the upper ends of 95 said bars, in order to hold said bars in place, and said rings can be lifted upwardly off of the bars for releasing the same.

The lower ends of the bars 72 and 73 are also held against the door 17, and, for this purpose, the plate 18 has horizontal slots 83, and the bars 72 and 73 and lower hinge straps 74 have open horizontal slots 84 to register with the slots 83, and said slots 83 and 84 have downwardly extending terminals 85 between the edges of the bars 72 and 73. Headed latch pins 86 are slidable in the slots 83, and when the bars 72 and 73 are swung against the auxiliary doors, the latch pins 86 can be slid into the slots 84 to drop 100 into the terminals or notches 85, and said latch pins will therefore hold the lower terminals of said bars against the door 17. By raising the pins 86 they can be slid out of the slots 84 and into the extended portions of the slots 83, thereby releasing the 105 lower terminals of said bars. 110

In order to hold the main and auxiliary doors closed under a single seal, a horizontal latch bar 87 is slidable in guides 88 on the outer side of the door 17 between the auxiliary doors, and has an offset terminal 89 to overlap the bar 72 when the bar 87 is slid toward said bar 72. An arm 90 is pivoted within a bearing 91 secured to the door 17 115 near the bar 73, to swing across said bar 73. The arm 90 and bar 87 are made to simultaneously engage the bars 72 and 73 by the provision of gear teeth 92 on the pivoted end of the arm 90 meshing within 120 125 130

the rack teeth 93 on the bar 87. Consequently, when the arm 90 is swung away from the bar 73 the bar 87 is slid away from the bar 72, and when the arm 90 is swung against the bar 73, the latch bar 87 is projected into engagement with the bar 72. A sealing hasp 94 is suitably connected to the free end portion of the arm 90 to engage over a keeper 95 carried by the car wall beyond the stop portion 25, for the reception of a seal, padlock, or the like, to hold the doors closed against unwarranted entrance into the car for purpose of theft.

In using the present door construction, the main door 17 is slid to closed position, thereby bringing the forward vertical edge portion thereof against the stop portion 25 behind the flange 26, and the keepers 35 will also project through the openings 33, with the latch bar 36 moved behind said keepers. The tongues 28 are also moved through the openings 28' in the stop portion 25 to engage the bolts 30, and said bolts are then tightened to clamp the forward edge portion of the door against the plate 24 of the post 16. The nuts 23 are also tightened to clamp the lower edge portion of the door against the sill, and by sliding the latch bar 36 downwardly, the cams 39 move behind the keepers 35 and will clamp the rear edge portion of the door against the plate 34 of the post 15. The main door 17 is now closed tightly against the door frame along the side and lower edges of the main door, to prevent leakage of grain, sand, or other similar material from the car, and to also exclude the elements from the door opening, so as to protect the contents. The lower auxiliary door 44 is then swung inwardly with the straps 51, to move the upper edge thereof into the groove 48, and said door is then slid upwardly to pass over the plate 18, and is then slid downwardly to move the lower edge of the door 44 into the groove 47, whereby said door 44 will bear outwardly at its upper and lower edges against the channel member 49 and upper edge of the plate 18, respectively, to prevent leakage, and to resist outward pressure against said door 44. The bolts 55 are then applied, which will prevent the door 44 from sliding off the straps 51 when the door is opened later on. Then, with the door 43 swung open upwardly, or removed from the straps 67, the material can be run into the car through the filling opening 45, and a chute can be inserted through said opening for delivering the material into the car. When the car is filled, and the door 43 slipped onto the straps 67, said door is swung inwardly and while in raised position on the straps 67 is moved against the frame 58, and then dropped to move the hook 64 and strip 66 behind the flanges 60 and 63, respectively. This will form a tight closure of the door 43 and will also resist

outward pressure against said door. The bolts 70 are then applied to prevent the door 43 from sliding off the straps 67, and the bars 72 and 73 are swung to overlap the end portions of the auxiliary doors 43 and 44. The latch rings 82 are moved down on the upper ends of said bars 72 and 73, and the latch pins 86 are moved into the slots 84, thereby fastening the upper and lower ends of said bars to the door 17. The arm 90 is then swung across the bar 73, thereby sliding the latch bar 87 to move the offset terminal 89 thereof over the bar 72, and the hasp 94 is then secured to the keeper 95 by the usual seal, padlock, or the like. Consequently, the main door 17 is not only held closed under the seal or lock, but the bars 72 and 73 are also held in place under such seal or lock, so that the bars cannot be swung away from the auxiliary doors. Consequently, the auxiliary doors cannot be opened without breaking the seal or lock, unless the required key for the lock is used.

The doors 17, 43 and 44 are therefore held tightly closed, and will be firmly held in place, to resist the pressure of the contents from within the car, and to also withstand the jostling of boxes, bundles or other objects behind the door, when the door is used for ordinary freight.

When it is desired to discharge the sand, grain, or other similar material from the car, the hasp 94 is first released from the keeper 95, thereby permitting the arm 90 to be swung away from the bar 73 and retracting the latch bar 87. Then, by disengaging the latch rings 82 and the latch pins 86 from the bars 72 and 73, said bars can be swung away from one another and away from the doors 43 and 44. The door 44 can now be raised and the lower edge lifted out of the groove 47, to swing said door 44 open outwardly to pass over the plate 18, in which event the door 44 can be slid downwardly to move out of the groove 48. If desired, the door 44 can be slid off the hinge straps 51 by removing the screws 55, if said door 44 is in the way or cannot be swung upwardly, as when the car is directly adjacent to a building or other object. The auxiliary door 43 can also be opened, if desired, for purpose of access into the car before the main door 17 is opened. When the door 43 is slid upwardly out of engagement from the frame 58, it can be swung open outwardly, and it can also be removed from the hinge strap 67 after the screws 70 are removed. The doors 43 and 44 can also be opened to dislodge boxes or other objects lodging against the door 17 from the inside, when it is desired to open the door 17, especially when used with freight shipped in boxes, packages, crates or the like.

In order to open the door 17, the bolts 30 and nuts 23 are loosened and the bolt 40 is

removed to enable the latch bar 36 to be raised, thereby releasing the side and lower edges of the door 17 from the door frame, and the door 17 can now be slid open, the 5 latch hooks 38 passing over the lugs 42.

In Fig. 12 there is shown an upper auxiliary door construction of modified form, resembling the lower auxiliary door 44 as hereinbefore described. Thus, the door 17' 10 has a groove 47' at the lower edge of the filling opening 45' behind a channel member 180 secured to the outer side of the door 17' to receive the lower edge of the door 43'. The door 17' has a groove 48' at the upper 15 edge of the opening 45' to receive the upper edge of the door 43' behind a channel member 49' secured to the door 17' in front of said groove 48'. An offset strip 56' is carried by the door 43' near its lower edge to 20 move in front of the upper edge portion of the member 180. The door 43' has guides 69' fitted on the hinge straps 67', which are hinged at their upper ends, as at 68', to the channel member 49' above the opening 45' 25 and said straps have the stop screws 70'. Chains or flexible elements 71' connect the door 43' and member 180, to prevent the loss of the door 43' when it is removed from the hinge straps 67'. The door 43' is closed 30 similarly to the door 44, the upper edge of the door 43' moving into the grooves 48', and the door 43' is lowered to move the lower edge thereof into the groove 47' after the door 43' has been moved inwardly across 35 the member 180. Vertical angle bars or cleats 77' (one of which is shown in Fig. 12) are secured to the door 43', similar to the cleats 77 of the door 44, for the engagement of stops 79' on the bars 72 and 73, for holding the door 43' down when said bars are 40 swung against the auxiliary doors and fastened.

Fig. 13 shows a modified device for holding the bars 72 and 73 and door 17 under a seal. Thus, a latch bar 87' is slidable in the guides 88' on the outer side of the door 17 and has the terminal 89' to engage over the bar 72, similar to the latch bar 87 hereinbefore described. An arm 90' is pivoted, as at 91', to the door 17, and swings upwardly and downwardly away from and across the bar 73, respectively. The arm 90' has an extension 92' connected by the link 93' with the bar 87', whereby when the arm 90' is swung across the bar 73, the link 93' pushes the latch bar 87' into engagement with the bar 72, and when the arm 90' is swung away from the bar 73, the link 93' pulls the bar 87' to retracted position, thereby simultaneously engaging and releasing the bars 72 and 73. A hasp 94' is hinged to the free end of the arm 90' to engage the keeper 95, and a keeper 96 is preferably carried by the door 17 behind which the arm 90' moves when swung across the bar 73, to

prevent the arm 90' from being pried away from the door.

In the construction shown in Figs. 14 to 21, inclusive, the main car door 170 is shown as composed of two layers of wood, the 70 boards 171 of the outer layer running vertically, while the boards 172 of the inner layer extend horizontally. In order to reinforce and stiffen the door 170, bars 173 of I section are disposed between the edges of the boards 75 172, as seen in Fig. 15, and the edges of said boards are fitted within said bars. Channel bars 174 are fitted on the edges of the boards 172 adjacent to the openings in the car door 170, and the bars 173 and 174 being of metal 80 will stiffen the door, as well as protecting the edges of the boards on the inner or rear surface of the door where subjected to the wear and tear from the contents of the car. The door 170 is suspended for longitudinal 85 movement along the exterior of the car wall from a suitable track 181.

A metal plate 180' is secured to the outer side of the door 170 along the lower edge or end thereof, and projects downwardly below said edge of the door, as seen in Fig. 15, and the lower edge portion of said plate is bent inwardly or rearwardly and upwardly to form a hook 190 which extends under and behind a depending flange 200 90 offset outwardly from a rail plate or strip 210 secured to the outer side of the car wall and sill 140. The offset portion of the strip 210 extends below the door 170, and the hook 190 in engaging under and behind the flange 100 200 will guide the door and maintain its position adjacent to the car wall. In order to support door 170 for free movement, should the door sag or the upper hanger yield, rollers 211 are mounted for rotation 105 within the lower edge portion of the door 170 within housings 212, and said rollers can roll on the offset portion of the strip 210, thereby preventing the door from binding or catching on said rail strip. 110

A vertical metal strip or plate 240 is secured to the outer side of the door post 160 and has a portion 250 bent outwardly at an angle to form a stop for the door, against which the forward vertical side edge of the door 170 strikes when the door is slid to closed position. The portion 250 has a flange 260 bent at an angle to overlap said portion of the door, and form a vertical groove or channel into which said portion of the door moves to hold the door against the post 160 and to prevent leakage. 115

A vertical Z-bar or strip 310 is secured to the opposite or rear vertical edge of the door and outer side thereof, and has a flange 125 320 extending from said edge of the door adjacent to the inner side of such door. A vertical plate or strip 340 is secured to the post 150 at the outer side thereof, against which the rear edge portion of the door 170 130

bears when closed, and said plate 340 has tongues or keepers 350 projecting from that edge opposite to the door opening to pass through openings 330 provided in the strip 5 310, so that when the door is closed the strip 310 will move over the keepers 350, which project through the openings 330 in front of the flange 320.

In order to latch the door 170 in closed position and to clamp the rear edge portion thereof against the plate 340, vertically spaced latches 360 are provided. These latches 360 are disposed in front of the flange 320, and each latch 360 has a longitudinal slot 371 engaging a rivet or headed stud 370 secured to the flange 320, permitting the latch to be slid longitudinally and swung in a plane parallel with and in front of the flange 320. Each latch 360 has a lug 380 extending outwardly at an angle from one end, the slot 371 being near one end of the latch and the lug 380 at the opposite end, and the studs 370 being so arranged as to be located below the keepers 350 when the door is closed, so that the latches 360 when swung upwardly, as indicated in dotted lines in Fig. 18, will move behind the keepers with the lugs 380 above such keepers. Doubled or U-shaped leaf springs 390 are secured to the latches 360, and such springs of the latches are located between the slots 371 and lugs 380, and are so arranged that when the latches are swung upwardly from depending position (from the full line to the dotted line position as seen in Fig. 18) the springs 390 wedge between the flange 320 and keepers 350, as seen in Fig. 20. The free terminals of the springs bear against the keepers 350, and the springs being compressed or the terminals thereof moved toward one another will create a rearward or inward pressure on the flange 320 to clamp the rear edge portion of the door tightly against the plate 340 on the post 150. Each latch 360 also has an outstanding lug 400 at that end opposite to the lug 380, and the keepers 350 have upstanding lugs 420 to prevent the lugs 380 from sliding off said keepers. The latches 360 normally hang down loosely, and when the door 170 is closed, said latches can be swung upwardly behind the keepers 350, the springs 390 being forced between said flange 320 and keepers 350, whereby to clamp the rear edge portion of the door against the door frame. The latches are then driven downwardly, such as by striking the lugs 380 with a hammer or other implement, so that the latches move longitudinally downward to bring the lugs 380 on the upper edges of the keepers 350. Such lugs 380 being in engagement with the lugs 420 will prevent the latches moving off the keepers, which will thereby latch the main door in closed position. The

latches 360 are released by driving them upwardly, such as by striking the lugs 400 from below, which will then permit the latches to be swung downwardly, the lugs 380 passing over the lugs 420. The door 70 170 can then be slid open when otherwise free to slide. Each keeper 350 preferably has a screw hole 410 therein to receive a set screw for either retaining the latch in position, or a wedge which can be driven downwardly behind the keeper for clamping the door in place, should the latch become broken off. 75

The auxiliary doors 430 and 440 are composed of metal, as shown, but are somewhat different than the auxiliary doors of the first form. Such doors are for the purpose of closing, respectively, an upper filling opening 450 in the door 170, near the upper end or edge of the main door, and a lower discharge opening 460 near the lower end or edge of the door 170. 80 85

The relief or discharge door or closure 440 is composed of the elongated sheet metal panel or cap 441 having its edge or 90 flange overlapping and secured to a stiff rim member 442 of angular cross section. A frame member 490 is secured to the outer side of the door 170 around the opening 460, and is provided at its inner edge with 95 an outstanding portion 491 having a flange 492 surrounding and extending from the opening. The door 440 is adapted to be disposed loosely over and around the outstanding portion 491 with the panel 441 100 bearing against the flange 492, and the rim member 442 bearing against the frame member 490. If desired, the rim member 442 of the door 440 can be secured to the frame member 490 and door 170 by means 105 of screws 443 when an especially tight fit is desired, although such securing means are not necessary for general purposes.

The door 440 is hingedly mounted on the main door 170 by means of depending straps 510 which are hinged, as at 520, to the door 170 above the opening 460 and frame member 490. Said hinge straps extend across the panel 441 and are secured thereto by means of rivets 540 or other securing elements, whereby the door swings with said straps outwardly and upwardly to open position, and downwardly and inwardly to closed position against the door 170 around the portion 491 of the frame member 490. The intermediate hinge strap 510 has an extension 550 projecting below the door 440 to be secured to the door 170 below the opening 460, such as by means of a securing screw or bolt 550. 110 115 120 125

In order to assist in holding the door 440 closed, arms 511 are hinged, as at 521, to the door 170 below the opening 460 near the opposite ends of the door 440, so that said arms can be swung upwardly to ex- 13

tend across the door 440 near the ends of the door, and the upper terminals of the arms 511 are secured to the door 170 above the door 440 by means of screws or bolts 551.

The upper auxiliary door 430 is slidable upwardly and downwardly on the outer side of the main door 170, instead of being hinged, and, as shown, is composed of sheet metal, and has a stiffening bar 431 secured thereto on the outer side between its upper and lower edges. The auxiliary door 430 is elongated horizontally, and the stiffening bar 431 will strengthen it. A horizontal weather strip 580 is secured to the door 170 above the upper opening 450 and is offset outwardly, as at 590, and has a depending flange 600 behind which the upper edge of door is moved when raised to closed position, and said strip will shed rain, snow, cinders, and the like, over the upper edge of the door 430 so they will not pass through the opening 450.

The door 430 is guided for vertical movement by a pair of vertical rail strips 610 secured to the outer side of the door 170 at the opposite ends of the opening 450 and extending downwardly for the movement of the door 430 to a position down below said opening. The strips 610 have the outstanding portions 611 across which the door 430 extends, and said portions have the flanges 612 bent to extend away from one another and away from the opening 450. The ends of vertical edge portions of the door 430 are bent back into hooks 650 extending across and behind the flanges 612, whereby the door is retained in place for movement along the rail strips 610 as well as preventing the entrance of rain, snow, or the like.

A horizontal strip 620 is secured to the door 170 at the outer side below the opening 450 and has an outstanding portion 621 with a depending flange 630, and the lower edge of the door 430 is bent back into a hook 660 to engage upwardly behind the flange 630, thereby also providing means for excluding the elements from the opening 450 when the door 430 is closed.

A hasp 670 is hinged to the door 430 to engage a keeper 680 carried by the door 170 above the weather strip 580, for supporting said door 430 in raised position. Stops 700 are carried by the door 170 to limit the downward movement of the door 430 when it is lowered.

In order to prevent the doors 430 and 440 from being opened, a pair of vertical bars 720 and 730 of channel form are hinged to swing between the upper and lower auxiliary doors with their ends below the lower edge of the door 450 and the lower ends of the bars overlapping the upper ends of the arms 511. Said bars 720

and 730 are secured to hinge straps 740, which are hinged as at 750 to the door 170 adjacent to the side edges thereof, whereby said bars are swingable about vertical axes away from and against the main door between the auxiliary doors. The bars 720 and 730 are movable over the rail strips 610 and will support the upper door 430, to prevent the same from being moved downwardly to open position, and the bars in overlapping the arms 511 will prevent the lower door 440 from being opened.

The main and auxiliary doors are held closed under a single seal in a manner closely resembling the latching and sealing device hereinbefore described, including a horizontal latch bar 870 slidable in guides 880 on the outer side of the door 170 below the stops 700. Said latch has an offset terminal 890 to overlap the bar 720 when the bar 870 is slid toward said bar 720. An arm 900 is pivoted within a bearing 910 secured to the door 170 near the bar 730, to swing across said bar. The arm 900 and bar 870 are made to simultaneously engage the bars 720 and 730 by the provision of gear teeth 920 on the pivoted end of the arm 900 meshing with rack teeth 930 on the bar 870. Consequently, when the arm 900 is swung away from the bar 730, the bar 870 is slid away from the bar 720, and when the arm 900 is swung across the bar 730, the latch bar 870 is projected into engagement with the bar 720. A sealing hasp 940 is suitably connected to the free end portion of the arm 900 to engage over a keeper 950 carried by the car wall beyond the stop portion 250, for the reception of a seal, padlock, or the like, to hold the doors closed against unwarranted entrance into the car for purpose of theft.

In using the door construction, the main and auxiliary doors are closed and secured, and released and opened, in substantially the same order as the doors 17, 43, and 44 hereinbefore described, with slight variations according to the changes or differences in construction, as will be apparent from the foregoing description.

Having thus described the invention, what is claimed as new is:—

1. A freight car door having upper and lower openings, auxiliary doors for said openings, a pair of bars supported from the car door for movement to be positioned between the auxiliary doors adjacent to the opposite ends thereof for holding the auxiliary doors closed and movable from between the auxiliary doors to permit them to be opened, and means for holding said bars when moved between the auxiliary doors.

2. A freight car door having upper and lower openings, auxiliary doors for said openings, a pair of bars carried by the car

door to move from positions beyond the ends of said auxiliary doors to positions between the auxiliary doors for holding said doors closed, and means carried by the car door for simultaneously engaging said bars for holding the doors closed.

3. A freight car door having upper and lower openings, auxiliary doors for said openings, vertical bars hinged to the car door to swing from positions beyond the opposite end portions of the auxiliary doors to positions between the auxiliary doors for holding the doors closed, and means carried by the car door for simultaneously engaging said bars for holding the doors closed.

4. A freight car door having upper and lower openings, auxiliary doors for said openings, vertical bars carried by the car door to hold the auxiliary doors closed, a sliding latch bar carried by the car door to engage one of said vertical bars, an arm pivotally connected to the car door to extend across the other vertical bar and adapted to be secured for holding the doors closed, and an operative connection between said latch bar and arm whereby they simultaneously engage and disengage the vertical bars.

5. A freight car door having upper and lower openings, auxiliary doors for said openings, the lower auxiliary door being hinged to swing open and the upper door slideable to open position, a bar carried by the car door to abut at its upper end the upper door for holding the upper door closed and the lower end portion of said bar being arranged for holding the lower door closed, and means for holding said bar.

6. A freight car door having upper and lower openings, auxiliary doors for said openings, the lower auxiliary door being hinged to swing open and the upper auxiliary door being slideable open downwardly, a bar carried by the car door to move to a position between said auxiliary doors, whereby the upper end of the bar supports the upper auxiliary door and the lower end of the bar holds the lower auxiliary door closed and means for holding said bar between the auxiliary doors.

7. A freight car door having upper and lower openings, auxiliary doors for said openings, bars hinged to the car door to swing about vertical axes at the opposite ends of the auxiliary doors for the movement of said bars toward and between the auxiliary doors and away from said auxiliary doors, the end portions of said bars being arranged to hold the auxiliary doors in closed position when said bars are swung between the auxiliary doors, and means carried by the car door for simultaneously engaging both of said bars when swung between the auxiliary doors.

8. A freight car door having an open-

ing, an auxiliary door for said opening, a pair of bars hinged to the car door to swing from positions beyond the opposite ends of said auxiliary door to positions to hold said auxiliary door closed, a latch bar 70 slidably carried by the car door to engage one of said bars, and an arm pivotally connected with the car door to extend across the other of the first named bars, said latch bar and arm having an operative connection whereby they simultaneously engage and disengage the first named bars.

9. A freight car door construction comprising a door frame, a door mounted for sliding movement, and means for latching and clamping the door to the frame including a keeper carried by one of said parts and a latch carried by the other, said keeper and latch being movable relatively in one direction for engagement to clamp the door against the frame and being movable relatively in another direction for latching the door to prevent it sliding open.

10. A freight car door construction comprising a door frame, a door mounted for sliding movement, and means for latching and clamping the door to the frame comprising a keeper carried by one of said parts and a latch connected to the other part for movement in different directions, the latch being engageable with the keeper by movement in one direction for clamping the door against the frame and the latch being engageable with the keeper by movement in another direction for latching the door closed.

11. A freight car door construction comprising a door frame, a door mounted for sliding movement, and means for latching and clamping the door to the frame comprising a keeper carried by one of said parts and a latch carried by the other part for swinging and sliding movements, said keeper and latch having cooperable portions to engage by the swinging and sliding movements of the latch, and said portions being so arranged that one movement of the latch into engagement with the keeper clamps the door against the frame and the other movement of the latch into engagement with the keeper latches the door closed.

12. A freight car door construction comprising a door frame, a door mounted for sliding movement, and means for latching and clamping the door to the frame comprising a keeper carried by one of said parts and a latch carried by the other, the latch having a spring portion to engage the keeper for pressing the door against the frame and the latch and keeper having portions to engage one another for latching the door closed.

13. A freight car door construction comprising a door frame, a door mounted for

- sliding movement, and means for latching and clamping the door to the frame including a keeper carried by one of said parts and a latch carried by the other part for 5 swinging and sliding movements, the latch having a spring portion to be swung with the latch into engagement with the keeper for pressing the door to the frame and the latch and keeper having portions to engage 10 by the sliding movement of the latch for latching the door closed. 14. A freight car door construction comprising a door frame, a door mounted for sliding movement, a keeper carried by the 15 door frame extending away from the door opening, a flange carried by the rear edge portion of the door to move behind said keeper when the door is closed, and a latch mounted on the outer side of said flange 20 to move between said keeper and flange for clamping the door against the frame. 15. A freight car door construction comprising a door frame, a door mounted for sliding movement, a keeper carried by the 25 door frame extending away from the door opening, a flange carried by the rear edge portion of the door to move behind said keeper when the door is closed, and a latch mounted on the outer side of said flange 30 to move between said keeper and flange for clamping the door against the frame, said keeper and latch having portions to engage one another for latching the door closed. 16. A freight car door construction comprising a door frame, a door mounted for 35 sliding movement, a keeper carried by the door frame and extending away from the door opening, a flange carried by the rear edge portion of the door to move behind said keeper when the door is closed, and means operable for exerting pressure between the keeper and flange for pressing the door against the frame and to also 40 latch the door in closed position. 17. A freight car door construction comprising a door frame, a door mounted for 45 sliding movement, a keeper carried by the door frame extending away from the door opening, a flange carried by the rear edge 50 portion of the door extending away from the door opening and adapted to move behind said keeper when the door is closed, and means on the outer side of said flange 55 to engage behind the keeper for pressing the door against the frame and to also engage the keeper for latching the door closed. 18. A freight car door construction comprising a door frame, a door mounted for 60 sliding movement, a keeper carried by one of said parts, and a latch carried by the other part to engage the keeper when the door is in closed position, and spring means to be disposed between the latch and keeper for pressing the door against the frame. 19. A freight car door construction comprising a door frame, a door mounted for 65 sliding movement, said frame and door having portions to be brought adjacent to one another in spaced relation when the door is closed, and spring means movable between 70 said portions in the space between them for pressing the door against the frame and removable from between said portions to release the door from the frame and to permit the door to be slid open. 75 20. A freight car door having an opening, an auxiliary door for closing said opening, a rail member carried by the car door for guiding the auxiliary door to and from said opening, and means for shielding said rail 80 member and holding the auxiliary door closed. 21. A freight car door having an opening, an auxiliary door to close said opening, a rail member carried by the car door 85 for guiding the auxiliary door, and a member movable to shield said rail member and to abut the auxiliary door and hold it closed. 22. A freight car door construction comprising a door frame, a door mounted for 90 sliding movement, a keeper carried by the door frame, a flange carried by the door to move behind said keeper, and a latch member having a slidable and pivotal connection 95 with said flange, said member having a spring to be swung with said member behind the keeper for pressing the door against the frame, and said member and keeper having portions to engage one another by the sliding movement of the member when swung behind said keeper. 100 23. A freight car door construction comprising a car door having an opening, rail members carried by said door at opposite 105 extremities of said opening, an auxiliary door slidable on said rail members to and from said opening, and means for retaining the auxiliary door over said opening including channel bars to be disposed over said rail members. 110 24. A freight car door construction comprising a car door having two openings, an auxiliary door for each of said openings, a rail member carried by the car door along 115 which one auxiliary door is movable to and from its opening, an arm carried by the car door to extend across the other auxiliary door, and a channel bar carried by the car door to move over said rail member and arm 120 for holding both auxiliary doors closed. 125 25. A freight car door construction comprising a car door having upper and lower openings, auxiliary doors for said openings, the lower auxiliary door being hinged to the car door to swing open, vertical rail members carried by the car door, the upper auxiliary door being slidable along said rail members downwardly from and upwardly to the upper opening, arms hingedly con- 130

nnected to the car door below the lower opening to swing across the lower auxiliary door, channel bars hinged to the car door to swing between the auxiliary doors over said rail

5 members and upper terminals of said arms for holding both auxiliary doors closed, and means for retaining said bars in place.

26. A freight car door construction comprising a freight car door having two openings, an auxiliary door for each opening, one door being slidable toward the other to open position, an arm carried by the car door to extend across the other auxiliary door, and a bar carried by the car door to be moved between the auxiliary doors to abut at one end

the first named auxiliary door for holding it closed and to overlap, at the other end, said arm.

27. A freight car door comprising boards having their edges disposed close together 20 and spaced apart, and metal strips between the adjacent edges of the boards for stiffening the door, each strip having oppositely extending flanges overlapping the corresponding edge portions of the boards for 25 protecting same.

In testimony whereof I hereunto affix my signature.

JOHN L. GUERRANT.
